UNITED STATES PATENT OFFICE.

GEORGE W. WILLARD, OF DETROIT, MICHIGAN.

DESIGN FOR A WINDOW-POLE AND PICTURE-HOOK HANGER.

SPECIFICATION forming part of Design No. 29,286, dated August 30, 1898.

Application filed April 29, 1898. Serial No. 679,247. Term of patent 14 years.

To all whom it may concern:

Be it known that I, GEORGE W. WILLARD, a citizen of the United States, residing at Detroit, county of Wayne, State of Michigan, have invented a new and original Design for a Window-Pole and Picture-Hook Hanger; and I declare the following to be a full, clear, and exact description of the invention, such as will enable others skilled in the art to which it appertains to make and use the same, reference being had to the accompanying drawings, which form a part of this specification.

In carrying out my invention, Figure 1 is a view in side elevation, showing my design. Fig. 2 is a view in elevation at right angles to Fig. 1. Fig. 3 is a vertical section of the device, and Fig. 4 a transverse cross-sectional view on the line 4 4, Fig. 3.

As shown in the drawings, the leading or material feature of my design consists of an upright shank or body A, having a hook A' projecting therefrom, on one side thereof, said hook being curved outward and upward from said body, the upper end of the hook being

offset from said body, as indicated at a. The 25 hook is also slotted, as indicated at a'. Above said hook projects an arm A² from said shank, said arm and said hook being on opposite sides of the body, the body on the side toward the hook being broadened at a², ribs a³, 30 projecting laterally from the body, forming the said flattened portion. The contour of the hook of the adjacent portion of the body forms a circular seat at the base of the hook, as indicated at a⁴. 35

Having described my invention, what I claim as new, and desire to secure by Letters Patent, is—

The design for a window-pole and picture-hook hanger, substantially as herein shown 40 and described.

In testimony whereof I sign this specification in the presence of two witnesses.

GEORGE W. WILLARD.

Witnesses:

N. S. WRIGHT,
MARY HICKEY.
